INSTALLMENT COLLECTING DEVICE

Migiel J. Uline, Washington, D. C.

Application June 9, 1937, Serial No. 147,320

5 Claims. (Cl. 194—19)

This invention relates to an installment collecting device in the form of a coin controlled clock having a locking bolt actuated thereby to prevent an article sold on the installment plan from being used after a predetermined time has elapsed until a coin is deposited therein to enable the clock to be rewound to release the locking bolt.

Another object of my invention is to provide a device in which the expansion and contraction of the main spring of a clock is utilized to operate a movable bolt to lock and unlock a movable member of the article whereby after a predetermined time has elapsed, the locking bolt will be moved into locked position by the expansion of the main spring so as to prevent the movable member of the article from being moved.

Another object of my invention is to provide a device which is exceedingly simple and cheap in construction and one in which I utilize the ordinary clockwork, as for example, of an eight-day clock so that after a predetermined time, as for example, seven days have elapsed, the main spring will force the locking bolt into locked position and will be held in that position until a coin is disposed in a coin chute which will release the winding post of the main spring in order to allow the same to be rewound and upon the completion of the rewinding of the clock, the bolt will be withdrawn from locked position to allow the article to be used for a certain time.

Other and further objects and advantages of the invention will be hereinafter set forth and the novel features thereof defined by the appended claims.

In the drawing,

Figure 1 is a front elevation of a refrigerator showing the application of my improved construction of installment collecting device;

Figure 2 is a front elevation of a radio showing the application of the same;

Figure 3 is a horizontal section of the casing; and

Figure 4 is a side elevation, the casing being broken away and shown partly in elevation.

In the embodiment of my invention as shown in Figure 1, I show the application of my improved collecting device to a refrigerator 1 by placing the device within the door 2 and providing a coin slot 3 and a keyhole 3'. It is, of course, understood that the device can be placed within the door frame and it will operate the same to lock the door.

In the embodiment of my invention as shown in Figure 2, I show the application of my col-

lecting device to a radio 4 provided with control knobs 5 which will be prevented from being turned by my improved locking device, a suitable coin slot 6 and a keyhole 6' being provided.

In carrying out my invention, I preferably arrange within a casing 7 clockwork such as used in the ordinary eight-day clock which is provided with a main spring 8 and as I only utilize the main spring of the clockwork in carrying out my invention, I have refrained from illustrating the entire clockwork as the clockwork will be of conventional form.

Disposed within the case 7 is a suitable bearing 9 in which I arrange a locking bolt 10 which is herein shown held in contact with the outer convolution of the main spring 8 by a coil spring 11, the inner end of the locking bolt being loosely connected as shown at 12 with the outer convolution of the main spring so that as the main spring expands and contracts, the bolt will be reciprocated into locked and unlocked position and while I have shown a reciprocating bolt, I wish it to be clearly understood that the bolt could be pivoted so long as it moved into locked or unlocked position by the expansion and contraction of the main spring and while I have shown the use of a coil spring 11 for normally holding the bolt in contact with the outer convolution of the main spring, by having the inner end of the bolt loosely connected to the outer convolution of the main spring by a thin strap or a piece of piano wire, the bolt will follow the movement of the spring as it contracts and expands.

A ratchet wheel 13 is fixed on the winding post 14 of the main spring 8 which is engaged by a pivoted pawl 15 normally held into engagement with the ratchet wheel in such a manner that the winding post cannot be turned by a key.

Disposed within the casing 7 is a coin chute 16 under which is arranged a coin box 17, said chute being of any desired configuration to prevent the fraudulent operation of the pawl as will be later described.

The pawl 15 is provided with a tail portion 15', which extends into the coin chute through a slot 16' so as to be in the path of travel of a coin passing through the chute. The pawl is preferably weighted to hold it in engagement with the ratchet wheel so that the weight of the coin in striking the same will overbalance the pawl and disengage it from the ratchet wheel.

In order to hold the pawl out of engagement with the ratchet wheel during the rewinding of the main spring of the clock, I dispose within the

casing a pivoted lever 18 having one end arranged in the path of travel of the pawl so as to allow the pawl to be disengaged by the weight of the coin, but will prevent the coin from passing by the tail of the pawl and the weight of the coin will hold the pawl disengaged until the clock is wound up. The other end of the lever 18 is held in contact with the main spring 8 by a coil spring 19 which causes the lever to follow the contraction of the spring so that after the main spring of the clock has been rewound, the lever 18 will move out of the path of the pawl and the coin will drop into the money box and the pawl will be released so as to allow it to drop back into engagement with the ratchet wheel and prevent the clock from being wound.

In the operation of the collecting device constructed in accordance with my invention, the article is sold on the installment plan with the understanding that the purchaser pays so much a week and as for example, if a refrigerator was sold on the 25 cents a week plan, the clock would be wound up and the door of the refrigerator could be opened and closed until after seven days have elapsed and at the end of this time, the bolt would start to work outwardly by the expansion of the spring in order to lock the door into closed position so that the refrigerator could not be used until the purchaser deposited a coin within the same which would release the winding mechanism and allow the clock to be rewound and as the clock is rewound, the spring contracts so as to draw the bolt out of locked position and allow the door of the refrigerator to be opened.

It is, of course, understood that the movement of the bolt is predetermined in respect to the movement of the clock spring in its expansion and contraction and that the weight of the pawl is predetermined in respect to the weight of the coin to be used.

By the use of a collecting device of this kind, any article having a movable member controlling the proper use of the same can be sold on the installment plan and it will not be necessary to collect the money deposited therein but once or twice a year, thereby saving a great deal of expense in collecting and providing a device which will insure the collection of the money due or else the article cannot be used.

While I have shown and described a collecting device utilizing a spring of a clock for operating the bolt by expansion and contraction, I wish it to be clearly understood that I do not wish to limit myself to the construction shown as my invention consists broadly in utilizing a clockwork for locking and unlocking a bolt for locking a movable member of the article sold to prevent it from being used in connection with coin controlled means to allow the clock to be rewound after it has run a predetermined length of time by inserting a coin.

The range of use to which the present invention may be put is wide and varied. For the purpose of illustration I have disclosed the same applied to a refrigerator and a radio. It may, however, be stated that the invention contemplates the application of the device to any article provided with a movable member which is adapted to be moved in the use of the same so that said device cannot be used after a predetermined time until a coin has been deposited therein.

In constructing a collecting device as herein

shown a casing is employed in which the mechanism is enclosed and is provided with a door having a lock so that the money deposited in the device can only be removed by the proper party and in installing in a refrigerator, the casing will be disposed either within the door or to the rear of the same and I wish it to be clearly understood that it is immaterial where the casing containing the device is placed so long as the locking bolt is disposed to engage a movable member to prevent the same from being operated.

What I claim is:

1. An installment collecting device comprising a clockwork provided with a main spring having a winding stem, a locking bolt having a connection with said spring and adapted to be moved into locked and unlocked position by the expansion and contraction of said spring, a ratchet wheel carried by the winding stem, a pawl movably held in engagement with said ratchet wheel and holding said pawl out of engagement with said ratchet wheel while said spring is being wound and means controlled by the contraction of said main spring for limiting the movement of said pawl.

2. An installment collecting device comprising a clockwork having a main spring, a movable bolt having a connection with said spring and adapted to be moved into locked and unlocked position by the expansion and contraction of said spring, a movable member movably held into a position for preventing the spring from being rewound and adapted to be released by a coin and means controlled by the contraction of said spring cooperating with said movable member for allowing said member to return to its normal position to prevent the rewinding of said spring.

3. An installment collecting device comprising a clockwork having a main spring provided with a winding stem, a locking bolt having a loose connection with said spring and adapted to be moved into locked and unlocked position by the expansion and contraction of said spring, a ratchet wheel carried by said winding stem, a pivoted pawl engaging said ratchet wheel adapted to be disengaged therefrom by a coin, means for limiting the movement of said pawl for holding said pawl out of engagement with said ratchet wheel, said means being operated by the contraction of said spring to release said pawl and allow said pawl to return to its normal position.

4. An installment collecting device for articles of manufacture having a movable member comprising a clockwork, a locking bolt adapted to cooperate with said movable member, means controlled by said clockwork for moving said bolt into locked position at a predetermined time and coin controlled means for preventing the rewinding of the clockwork.

5. An installment collecting device for articles of manufacture having a movable member, comprising a clockwork, a locking bolt operated by said clockwork and adapted to be moved into engagement with said movable member when the clockwork runs down and out of engagement with said movable member when the clockwork is wound up and coin-controlled means cooperating with said clockwork for preventing the rewinding of the clockwork when said clockwork runs down.

MIGIEL J. ULINE.
